BLANCHE CERVELLI

BY *Linck Johnson*
ATTORNEY

UNITED STATES PATENT OFFICE.

BLANCHE CERVELLI, OF SAN FRANCISCO, CALIFORNIA.

FACIAL PACK.

Application filed July 5, 1927. Serial No. 203,327.

This invention relates particularly to a water proof casing shaped to fit the chin and jaw of the human head and which is adapted to be filled with crushed ice or a 5 warm fluid to apply a cold or hot temperature to the facial muscles and skin adjacent the chin and jaw.

An object of the invention is to provide a facial ice-pack device shaped to conform 10 to the contour of the chin and jaw, and adapted to be filled with crushed ice to apply the ice application directly onto all parts of the face, covered by the device.

A further object of the invention is to 15 provide a facial ice pack casing adapted to contain ice, having the side thereof that contacts with the face adapted to snugly engage therewith and not to bulge away therefrom, the outer wall of the casing being so constructed that the bulges and irregularities in the ice will force the outer 20 part of the casing outward away from the face without affecting the placement of the inner wall of the casing.

25 Other objects of the invention are to provide a facial ice pack casing that will be superior in point of simplicity, inexpensiveness of construction, positiveness of operation, and facility and convenience in use 30 and general efficiency.

In this specification and the annexed drawings, the invention is illustrated in the form considered to be the best, but it is to be understood that the invention is not limited 35 to such form, because it may be embodied in other forms, and it is also to be understood that in and by the claims following the description, it is desired to cover the invention in whatsoever form it may be 40 embodied.

In the accompanying one sheet of drawings

Fig. 1 is a perspective view of my fluid casing applied in operative position to the 45 head of a wearer.

Fig. 2 is a plan view of the casing.

Fig. 3 is a section taken through Fig. 2 on the line 3—3.

Fig. 4 is a section taken through Fig. 2 50 on the line 4—4.

Fig. 5 is a section through the casing showing the outer wall in a collapsed condition.

In detail, the construction illustrated in 55 the drawings comprises a casing to contain

cracked ice, or warmed fluid to enable said temperate medium to be placed in contact with the face of a person desiring to strengthen the facial muscles or skin. The casing is substantially crescent shaped, and 60 consists of an inner wall 1 having a depression 2 moulded therein to fit the chin of a person using the device.

The width of the inner wall 1 is predetermined, and said wall is so shaped that 65 it will snugly engage around the chin and jaw of a human head. An outer wall 3 is secured along its perimetral edges 4 to the edges of the inner wall. The outer wall 3 is of greater width than the inner wall, 70 as shown in Fig. 5, so that when the casing is in an empty or collapsed condition, the outer wall will tend to sag with respect to the inner wall. By making the outer wall 3 of greater width than the inner wall 1, 75 the warming or the chilling medium that is introduced into the casing will cause the said outer wall 3 to be expanded away from the inner wall 1, without causing the inner wall to be lifted away from contact with 80 the face.

The casing is arranged on the head by placing the moulded depression 2 on the inner wall 1 around the chin and then wrapping the two opposite ends 5 and 6 of the 85 casing around so as to cover the jaw. This placement of the casing thus positions it to apply heat or cold to the facial muscles desired to be strengthened or to the skin covering the chin and jaw. Each of the opposite ends of the casing are connected together by a strap 7, which is passed over the top of the head of the wearer, thus providing a simple and effective means for holding the casing on the head. 90

The outer wall 3 of the casing at a point approximately underneath the chin is provided with a port 8 therein closed by a removable cap 9. Cracked ice or a warming fluid is introduced through the capped port 8 into the interior of the casing and the filling medium is drained from the casing through the same port. In Fig. 3 I have shown the relative positions of the capped port 8 and the chin and I have also indicated the approximate position, of the chin with respect to the cavity 2 provided on the inner wall 1, which is shaped to receive the chin. By shaping the inner wall 1 which comes in contact with the skin 110

around the jaw and chin, to the contour of the chin, it enables the casing to be held close to the face and the outer wall, which is of greater width than the inner wall, will 5 expand or bulge when filled with the heating or cooling medium without causing the inner wall to be bulged or distorted from its selected position on the head.

Having thus described this invention, 10 what I claim and desire to secure by Letters Patent is:

1. A casing formed of waterproof material and having means therein through which ice can be introduced into the interior 15 thereof, said casing having one side thereof shaped to fit the contour of the chin and jaw of a human head and the opposite side 20 expansible to accommodate the ice; and means secured to the opposite ends of said casing to hold said casing in a selected position on the chin and jaw.

2. A casing of waterproof material, comprised of two sheets secured together along their outer edges, one sheet being of greater 25 width than the other and having means therein through which ice can be introduced into the casing formed of the two sheets, the sheet of lesser width being moulded to fit the contour of the chin and jaw; and means 30 secured to the opposite ends of said casing to hold said casing in a selected position on the chin and jaw.

3. A flexible fluid container formed of two sheets of crescent-shaped, waterproofed material joined together along the perimetal edges, one sheet being shaped to conform to the contour of the chin and jaw and the other sheet being of greater width than the first mentioned sheet to accommodate the fluid without distorting the shape of said 40 first mentioned sheet; means in the larger sheet through which fluid can be introduced into the casing, and means secured to the opposite ends of said casing to hold said casing in a selected position on the chin and 45 jaw.

4. A flexible fluid container formed of two sheets of crescent-shaped waterproofed material joined together along the perimetal edges, one sheet being shaped to conform 50 to the contour of the chin and jaw and the other sheet being of greater width than the first mentioned sheet to accommodate the fluid without distorting the shape of said 55 first mentioned sheet; a removable plug in the larger sheet through which fluid can be introduced into the casing; and means secured to the opposite ends of said casing to hold said casing in a selected position on the chin and jaw.

In testimony whereof, I have hereunto set my hand at San Francisco, California, this 20th day of June, 1927.

BLANCHE CERVELLI.
